UNITED STATES PATENT OFFICE.

EDMOND BURKE KNAPP, OF SAN JACINTO, CALIFORNIA.

HARNESS-LOOP.

SPECIFICATION forming part of Letters Patent No. 400,461, dated April 2, 1889.

Application filed November 30, 1888. Serial No. 292,312. (No model.)

To all whom it may concern:

Be it known that I, EDMOND BURKE KNAPP, a citizen of the United States, residing at San Jacinto, in the county of San Diego and State of California, have invented a new and useful Improvement in Keepers or Slides for Hip-Straps, of which the following is a specification.

The invention relates to keepers or slides for hip-straps; and it consists in a certain novel construction and combination of devices, fully described hereinafter in connection with the accompanying drawings, and specifically pointed out in the appended claim.

15 In the drawings, Figure 1 is a perspective view of a keeper or slide embodying my improvements applied in the operative position to a portion of a back-strap. Fig. 2 is a perspective view of the keeper or slide detached from the strap. Fig. 3 is a central sectional view of the keeper or slide taken transversely. Fig. 4 is a transverse section of the same.

Referring by letter to the drawings, A designates the back-strap, and B designates the keeper or slide, which is secured thereto near its rear end.

25 C designates the base of the improved keeper or slide, which is provided with a series of perforations, c c, registering with similar 30 perforations in the back-strap and engaged by suitable rivets, c' c'.

D D designate the front and rear sides of the keeper integral with the said base, and E E designate the top bars of the keeper, integral with the sides and connecting the corresponding ends of the same. The center of the keeper is open, thereby rendering it lighter and enabling the center rivet, c², to be reached.

F represents the hip-strap, which passes at 40 its center over the base beneath the top bars, and is held by the latter in contact with the base, the said strap being at the same time allowed free movement in the keeper. The

upper surface of the base is rounded convexly, so as to present no sharp edges to engage the hip-strap. 45

The improved keeper or slide is adapted to be made of hard rubber or gutta-percha, so as to be strong and at the same time inconspicuous when attached to the back-strap; 50 but it is obvious that it may be made of metal or any other material of suitable strength.

The ordinary method of attaching the hip-strap to the back-strap is to form a loop of leather on the under side of the latter, through 55 which the former passes; but this is objectionable, for the reasons that the motion of the hip-strap wears on the back-strap and the loop thereon, thereby enlarging the latter, and, permitting too much motion in the hip-strap, the 60 back-strap is injured by the said wear, the loop is liable to be torn off by a severe strain, and the lump or enlargement formed by the crossing of the straps is liable to chafe the back of the horse. 65

Having thus described my invention, I claim—

As an improved article of manufacture, the keeper for hip-straps, having a convexly-rounded base provided with a suitable number of perforations to receive rivets, the sides 70 D D, integral with the base and adapted to bear against the edges of the strap, which is passed over the base, and the top bars, E E, connecting the corresponding ends of the sides 75 D and extending over the said strap, the said bars being integral with the sides, all constructed and arranged substantially as specified.

In testimony that I claim the foregoing as 80 my own I have hereto affixed my signature in presence of two witnesses.

EDMOND BURKE KNAPP.
